APPARATUS FOR STACKING POWDER GRAINS

Robert Van Roo, United States Army,
West Point, N. Y.

Application January 5, 1942, Serial No. 425,646

5 Claims. (Cl. 226—2)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a device for stacking cylindrical objects, and more particularly to a machine for superimposing numerous parallel rows of powder grains end on end.

An object of the invention is to provide a simple, sturdy device for quickly and conveniently stacking powder grains in a container.

The specific nature of the invention as well as other objects and advantages thereof will clearly appear from a description of a preferred embodiment as shown in the accompanying drawings in which:

Fig. 1 is a view in side elevation of the stacking machine in its initial position.

Fig. 2 is a plan view of the device with the hopper removed to better illustrate the invention.

Fig. 3 is an enlarged view in side elevation with parts removed of one of the devices for feeding a series of powder grains to the oscillating ram.

Fig. 4 is a plan view of one of the above mentioned devices.

Fig. 5 is an enlarged central vertical sectional view of the oscillating ram.

Fig. 6 is a bottom plan view of the ram showing its hinged mounting.

Fig. 7 is a central vertical sectional view of the ram tilted to transfer powder grains to a container, and

Fig. 8 is a diagrammatic showing of a battery of stacking machines positioned about a hopper.

Referring to the drawings, loose powder is received in a hopper 9 of conventional design which contains an agitator (not shown). The agitator operates in a well known manner to feed a series of cylindrical powder grains 10 axially into each of a group of four substantially vertical feed tubes 11. The lower ends of the tubes discharge into a set of four converging horizontal guideways 12 which intersect at a common junction 13, see Fig. 2. The superimposed cylindrical powder grains 10 in the feed tubes 11 form four upright columns with the lowermost grains resting in the troughs of the guideways as shown in Fig. 3. Each guideway 12 is provided with a rotating device 14 for advancing or indexing the powder grains 10 to the right as viewed in Figs. 1-4 and away from the discharge opening 15 of a feed tube 11. The discharge opening is elevated above the bottom face of the guideway a distance slightly in excess of the length of a grain.

Each rotating device 14 comprises a plurality

of spaced, propeller-like rotors 16 mounted on a vertical shaft 17 and driven by a sheave 18 coupled to a suitable power source (not shown), see Figs. 3 and 4. The number of rotors employed on a single shaft is determined by the length of the grain structure. The shaft 17 may be conditioned to permit the removal or addition of rotors in accordance with the length of the grain structure being operated upon. Likewise the feed tubes are preferably adjustable in height to accommodate longer grains to permit the displacement of the grains from the discharge opening 15 by the spaced rotors 16. The ends of the guideways near the feed tubes 11 are slotted at 17' to permit the rotors 16 to pass therethrough and come into engagement with the pellet or grain at the discharge opening 15 of a feed tube. Each arm 19 of a rotor 16 is provided with an arcuate edge 20 preferably having the configuration of an involute spiral. These edges are adapted to periodically engage powder grains which are directly under the discharge tubes and push them to the right as indicated in Figs. 3 and 4.

The rows of powder grains 10 are forced to the right in the guideways 12 as indicated in Fig. 2, and converge at the junction 13 adjoining a disk-like ram 21. The face of the ram is then level with the bottom of the guideways 12. The periphery of the disk slidably engages a vertically extending wall or collar 22 which has a cut-out portion 23 at the end of junction 13. The powder grains are forced or slid on to the ram 21 with their axes remaining perpendicular to the plane of the disk by the action of the rotors which are exerting pressure on succeeding pellets. When the ram is full of pellets the movement of the rotors is stopped.

Ram 21 has fixed to its base a vertically depending plunger 24 provided with a recess 25. The plunger is slidably mounted in a sleeve 26 which is secured to a pair of radially extending horizontal arms 27, see Fig. 6. These arms are in turn secured to a U-shaped rod 28 which is pivoted at its ends to a fixed support 29. The collar 22 is secured to the arcuate portion 30 of the U-shaped rod 28 by suitable means such as welding. Integral with the sleeve 26 is a horizontal tubular member 31 which houses a spring urged reciprocating bolt 32 as shown in Fig. 5. The bolt is arranged for selective engagement with the recess 25 and is controlled by an operating rod or lever 33 which is coupled to the projecting end of the bolt. The bolt 32 is normally held in the recess 25 by the action of the spring. The lower end of the plunger 24 is coupled to the

piston of a fluid cylinder 34 through a suitable linkage connection 35.

When valve 36 is operated, fluid is admitted into the bottom of cylinder 36 and the piston moves upwardly. Ram 21 is thereby tilted 90° to the right as shown in Fig. 7 and the layer of powder grains 10 is now vertically arranged. The collar is presented in accurate alignment with a ring 37 which is secured to the side of a carriage 38. The carriage is arranged to support a pair of cylindrical containers 39 whose nominal diameters are that of the size charge desired. One end of the container 39 rests in an annular groove 40 in the ring 37 and serves to orient the container in alignment with the grain confining collar 22 on the ram. A suitable automatic latch 41 detachably retains the container in the annular groove. A transfer of the layer of powder grains to the container 39 is effected by retracting the bolt 32 from the recess 25 in the plunger 24. This enables the fluid motor to displace the plunger and its interconnected ram to the right as shown in Fig. 7. The ram moves relative to the presently stationary collar 22 and the layer of powder is pushed or transferred into the container 39.

The container 39 is provided with a cylindrical disk follower 42 (Figs. 5 and 7) which is slidably mounted therein and is held in place by friction. This follower is placed in contiguous relationship with the ends of the incoming layer of powder grains and advances to the right as the powder is forced into the container. The follower maintains the grains in their previously stacked relationship.

When the valve is operated in a reverse direction, the plunger is retracted and latched and the ram is swung 90° back to the initial horizontal position shown in Fig. 5. The rotors 16 are again put into operation until the ram is filled with a layer of powder grains whereupon the rotors are stopped. The ram is once more tilted, unlatched, and an additional layer of grains is expressed from the confining collar 22 and forced into the container 39. This operation advances the previously deposited layer and the follower 42 an additional increment of distance into the container. The operation is repeated until the container is full whereupon a transfer from the container to a silk bag is effected in accordance with the present well known practice.

The carriage 38 which supports the containers 39 moves on a suitable track 43. Two containers are mounted in a predetermined spaced relationship on the carriage so that an empty can is always maintained in readiness to receive a powder charge. When one can is filled, the carriage is indexed or moved on its rails 43 a predetermined distance so that the empty can is presented in accurate alignment with collar 22 about the tilting ram 21. In accordance with one method a pin 44 may be slipped through an aperture 45 in a leg of the carriage and a corresponding aperture 46 in the rail thereby insuring proper alignment of a container 39 with the collar on the ram.

Fig. 8 is a diagrammatic representation of a battery of loading machines placed about a common hopper 10. Four machines positioned 90° apart are fed from the hopper and enable operations to proceed at a rapid rate while utilizing but a small work space.

The operation of the device has been explained in conjunction with the description of the component parts.

I claim:

1. In a machine for arranging cylindrical bodies in a layer in a container with their axes in a parallel relationship, a guideway for a series of vertically disposed cylindrical bodies, a rotary cam for moving the bodies in the guideway, a substantially horizontal platform communicating with one end of the guideway, a support slidably engaging the platform, said support arranged for rotation about a horizontal axis, latch means interconnecting the support and the platform whereby relative movement therebetween is selectively controlled, a collar on the support in sliding engagement with the periphery of the platform, said collar extending above the face of the platform substantially the length of a cylindrical body and having an opening at the end of the guideway, means for rotating the support and platform to a vertical position, said means also adapted to displace the platform in the collar upon release of the latch means whereby the bodies are transferred in a layer to a container abutting the end of the collar, said support rotating means also arranged to return the platform and support to the initial position after a transfer of cylindrical bodies.

2. In a machine for arranging cylindrical bodies in a layer in a container with their axes in a parallel relationship, converging guideways for a plurality of series of vertically disposed cylindrical bodies, rotary cam means for moving the bodies in the guideways, a substantially horizontal platform adjoining the converging ends of the guideways, a support slidably engaging the platform and arranged for rotation about a horizontal axis, latch means interconnecting the support and the platform whereby relative movement is selectively controlled, a collar on the support in sliding engagement with the periphery of the platform, said collar extending above the face of the platform substantially the length of a cylindrical body and having an inlet at the end of the guideways, means for rotating the support and platform to a vertical position, said means also adapted to displace the platform in the collar upon release of the latch means whereby the bodies are transferred in a layer to a container abutting the end of the collar, said support rotating means also arranged to return the platform and support to the initial position after a transfer of a layer of cylindrical bodies.

3. In a machine for arranging bodies in a layer in a container with their axes in parallel relationship a guideway arranged to receive a series of vertically disposed bodies, means for moving the bodies in the guideway, a platform positioned to receive the bodies in vertical position and while the platform is in horizontal position, a rod below the platform and pivoted for movement from horizontal to vertical position, a cylinder carried by said rod, a plunger in said cylinder and secured to the platform, latch means for interconnecting the cylinder and plunger whereby the relative movement therebetween is controlled, a collar on said rod and engaged by the periphery of the platform, said collar serving to guide the platform and maintain the bodies thereon, means for operating the plunger to rock the rod and platform to vertical position, said means also serving to actuate the platform when in vertical position with respect to the rod and collar to transfer the bodies in a layer to a container, and return the rod, collar and platform to normal position after the transfer.

4. In a machine for arranging bodies in a layer

in a container with their axes in parallel relationship, a guideway arranged to receive a series of vertically disposed bodies, means for moving the bodies in the guideway, a platform arranged to receive the bodies in vertical position, a rockable support for the platform, means for rocking the support and platform from horizontal to vertical position, a movable connection between the support and platform, and means for retaining the bodies in parallelism on the platform in all contemplated positions of the platform, the means for rocking the platform from horizontal to vertical position also serving to actuate the platform when in vertical position to transfer the bodies in a layer to a container.

5. In a machine of the character described, a guideway arranged to receive a series of vertically disposed bodies, means for moving the bodies in said guideway, a rockable platform positioned to receive said bodies in vertical position while the platform is in horizontal position, a rockable support for the platform, a movable connection between said support and platform, means for rocking the platform from horizontal to vertical position and returning the platform to horizontal position, said means also serving to actuate the platform when in vertical position to transfer the bodies to a container.
